UNITED STATES PATENT OFFICE.

F. JONES, OF PRESCOTT, WISCONSIN.

ROLLER ATTACHMENT FOR BREAST-STRAPS.

Specification forming part of Letters Patent No. 40,045, dated September 22, 1863.

To all whom it may concern:

Be it known that I, F. JONES, of Prescott, in the county of Pierce and State of Wisconsin, have invented a new and useful Roller Attachment for the Breast Straps of Double Harness; and I do hereby declare that the following is a full, clear, and exact description of the same, reference being had to the accompanying drawings, making a part of this specification, in which—

Figure 1 is a section of my invention, taken in the line $x x$, Fig. 2; Fig. 2, a side view of the same; Fig. 3, a perspective view of a breast-strap and neck-yoke, with my invention applied to it.

Similar letters of reference indicate corresponding parts in the several figures.

The object of this invention is to obtain a simple means to prevent horses in double harness being shoulder-jammed, and also prevent the friction and rubbing on the shoulders of horses, caused by the lateral motion of the ordinary breast-straps, as well as to prevent the wear of the breast-straps caused by the rubbing of the same through the rings which connect them to the neck-yokes.

To enable those skilled in the art to fully understand and construct my invention, I will proceed to describe it.

A represents a frame, constructed of any suitable metal or other material, and formed with three sides—two of which, $a a$, are parallel with each other and the other one, a' , which connects $a a$ at right angles to the latter, as shown more particularly in Fig. 2.

To the center of the side a' of the frame A there is a hook, b, and between the outer parts of the sides $a a$ there is fitted a roller, B, which is of metal or other material, and provided at each end with a circular flange, c, the inner surfaces of which are beveled or

rounded, as shown clearly in Fig. 2. This roller is provided at each end with a journal fitted in the sides $a a$, so as to turn freely therein, or a shaft may be secured between the outer parts of the sides $a a$ and the roller B fitted loosely upon it.

In the inner surface of each side piece a there is made a recess, d, to receive the edges of the flanges c of the roller, as is also shown clearly in Fig. 2.

The invention is applied and used as follows: The hooks b are fitted in the rings at the ends of the neck-yoke, the latter being attached to the end of the draft-pole, as usual, (see Fig. 3,) and the breast-straps pass around the roller B and are attached to the hames of the collars, as usual. The rollers B, it will be seen, admit of the breast straps working freely, preventing the straps from being chafed and worn, and also preventing shoulder rubbing or jamming caused by the old mode of attachment, which does not admit of the free working of the breast straps.

By having the flanges c of the rollers fitted in the recesses d in the inner surfaces of the sides $a a$ of the frames A, the breast-straps are prevented from catching on the edges of the flanges and a free movement allowed the former in all cases or at all times.

Having thus described my invention, what I claim as new, and desire to secure by Letters Patent, is—

The frame A, provided with the roller B and the hook b, when applied to the neck-yoke and breast-straps, substantially as and for the purpose specified.

F. JONES.
